FIREARM

Roy Clifton Robertson, Pocahontas, Miss.

Application March 28, 1935, Serial No. 13,535

6 Claims. (Cl. 42—21)

The present invention relates to new and useful improvements in the general art of firearms and more especially to firearms of the rifle type.

An important object of the invention is to provide a gun wherein cartridges are stored in a special magazine which will permit the ready use of a much greater quantity than can be retained in repeating rifles of present day constructions.

Another important object of the invention is to provide an improved rifle that can be used as a repeater or for single shots, with the change-over capable of being made by a simple manipulation.

Still another important object of the invention is to provide a rifle employing but a single trigger which can be set for automatic firing, single or repeating fire.

Various other important objects and advantages of the invention will become apparent to the reader of the following specification.

In the drawings:

Fig. 1 represents a side elevational view of the gun without the stock.

Fig. 2 represents a longitudinal sectional view through the intermediate portion of the gun.

Fig. 3 represents a fragmentary sectional view taken substantially on line 4—4 of Fig. 2.

Fig. 4 represents a fragmentary vertical sectional view through the breech portion of the rifle showing a cartridge being forced toward the firing chamber.

Fig. 5 represents a perspective view of the guide spring.

Fig. 6 represents a perspective view of the right claw arm.

Fig. 7 represents a bottom plan view of the magazine.

Fig. 8 represents a perspective view of the forward holder for the magazine.

Fig. 9 represents a plan view of the cam employed with the magazine securing means.

Fig. 10 represents a side elevational view of the cam shown in Fig. 9.

Fig. 11 represents a perspective view of the rocker bar cartridge guide.

Referring to the drawings, wherein like numerals designate like parts, it can be seen that numeral 5 represents the barrel of the rifle which is threaded at its inner end into the forward end 6 of the breech casing, the same being bored as at 7 for the reception of the cartridge.

Numeral 8 represents the guide-way for the block 9. This block 9 is recessed to receive the forward end of the recoil spring 10 which is con-

cealed in the guide way 8, the same being convoluted around the guide rod 11.

The stock frame 12 has the breech casing secured thereto by the tapered pins 13 and the rear end of this frame carries suitable tangs 14 whereby the same can be secured to the usual wooden stock (not shown). This frame 12 includes a left and a right wall spaced apart between which mechanism is mounted which will be described hereinafter.

The block 9 is provided with the conventional firing pin 15, while disposed through the lower portion of the rear end of this block is a pin or bolt 16, equipped at one end with a head 17 and at its opposite end with a laterally extending handle 18 disposed through a slot in the wall of the guideway 8. A claw arm 19 is provided on the left side of the block 9, while a claw arm 20 is provided on the right side of the block and each is provided with an opening at 21 its rear end through which the aforementioned pin or bolt 16 passes.

From the rear end of the arm 20 depends a protuberance 21 defining a shoulder. Springs 24 are provided on the end portions of the pin 16 to maintain the arms 19—20 against the block 9, and it is to be understood that the openings in the rear ends of the arms 19 and 20, are sufficiently large to permit a substantial outward movement of the forward forked ends 25 of these arms 19—20. As is clearly shown in the drawings, the ends 25 converge inwardly toward each other, each being provided with reduced lugs 26—27, the same serving as claws so as to readily hook behind the head of a cartridge.

It can be observed that numeral 28 represents a pusher member carried by the block 9 which serves to push the cartridge forwardly after the cartridge has been placed in front of the block by one of the claws or hooks 28. The magazine for the gun is generally referred to by numeral 30 and its rear end protrudes into the holder 31 at the rear end of the barrel 5. The bottom side of the holder 31 is provided with a small rod guide 33.

The magazine generally referred to by numeral 30 includes an elongated shell 35 of rectangular cross section, and this shell is provided with a longitudinally extending slot 36 on the bottom side thereof. The forward end of this magazine 30 is provided with an enlarged head construction 37 which permits easy grasping and on this head is a lug 38, the same being on the bottom side thereof.

It will be observed that numeral 39 represents

a forward holder for the magazine 30, the same having a bottom portion 40 on which the detent 41 is swingably mounted, the said detent having a cam projection 42 on its inner side 5 which is capable of engaging with the lug 38 on the magazine head 37 to secure the magazine head to the holder 39 so that these cannot be displaced. Numeral 43 represents a loop or strap on the holder 39 for snugly surrounding the 10 lower end portion of the barrel 5.

Operative in the magazine shell 35 is the follower, which includes the outside plate 44 connected to the internal cartridge-engaging member 45 by pins or connectors 46. An elongated compressible coiled spring 47 is interposed in the shell 35 between the head 37 and the member 15 45 of the follower.

Obviously by moving the follower back in the shell 35 towards the head 37, (if the tension becomes too great to permit hand insertion of the 20 cartridges against the tension of the spring), the tension of the spring will be released sufficiently to make the insertion of the cartridges convenient and without difficulty.

In further carrying out the construction of the magazine, it will be seen that the bottom side of the magazine 35 is extended to provide a lip 48, while the top side of the shell is extended and bifurcated to provide the pair of downwardly 25 curved spring fingers 49-49 and the side walls 30 of the magazine are extended to provide small extensions 50, one for each side of the magazine and these are spaced from the lip 48 and fingers 49, as in the manner substantially shown in Fig. 35 7, and these serve to prevent lateral displacement of the cartridges.

It can now be understood that the cartridges are placed in the shell 35 in alternate fashion with their cap or firing ends in oppositely disposed positions. In other words, only alternate 40 cartridges have their firing ends against the same side of the magazine shell.

An examination of Fig. 3 will now disclose the cartridge receiver which includes a plate 51 having a reduced neck portion 52 at its rear end in which are the longitudinally extending slots 45 53-53. The plate 51 at the point where it merges with the neck 52 has a substantially V-shaped plate 54 secured thereto by a screw or like 50 securing member 55, the same also serving as an abutment for the outer end of the lip 48 on the magazine, and which lip rests upon the plate 51. The aforementioned fingers 49-49 are as before stated, above the lip 48 but terminating inwardly 55 thereof while a spring 56 secured to the aforementioned rear magazine holder 31 extends rearwardly for disposition over the cartridge-receiving plate 51. This plate 56 is of spring material and bifurcated from its rear end forwardly as 60 at 57.

The furcations 58, thus formed have inner edge portions cut away so as to provide a passageway between the free end portions of the same, in which a cartridge can be steadied and guided. 65 The cut-away furcations terminate at their outer ends above the V-shaped plate 54. Attention is directed at this time to the channeled flanges 59 which extend along the longitudinal edge portions of the plate 51 and the neck 52 thereof, the 70 flanges extending forwardly of the plate 51 as at 59^a, and serving as tracks for the claw heads 25 on the arms 19-20, the claw heads 25 being cut away as at 25^a to receive said flanges 59 in the manner apparent in Figure 6. Supported 75 beneath the plate 51 is a rockable guide 60 which

is provided with a radially extending cavity 61 extending inwardly from its periphery, in the flanges 62-62 which operate through the aforementioned slots 53-53 in the neck portion 52 of the plate 51 (see Fig. 3). Pivotedly connected 5 to the rockable guide 60 is a rod 63 which extends downwardly and operates through an opening in the brace bar 64 (see Fig. 4). A spring 65 is interposed between the brace bar 64 and the guide 60 so as to retain the guide always off-center so that its operation is solely dependent upon the actuation of the block 9.

Located above the spring plate 56 and pivotedly connected at its upper end to the forward end 6 of the block 9 is the swingable guide 66, the 15 same being clearly shown in Figs. 2 and 4. This swingable guide is in the form of an incline having side flanges 67 between which a cartridge can be guided while in movement toward the chamber 7, the bottom of this guide being provided with a cleat 68.

Numeral 69 represents the hammer which is bifurcated to provide depending leg members 70-71. The hammer 69 is swingably supported on the pin 73, the pin extending through the 25 opening in the legs 71.

Pivotedly secured to the hammer 69 at the point 74 between the leg members 70-71 is the angularly shaped member 75 from the outer portion 76 of which extends the elongated guide rod 30 77 which passes through a guide 78 on the inner side of the stock frame 12.

A coiled compressible spring 79 is convoluted on this rod 77 and interposed between the portions 76 of the member 75 and the said guide 78. 35

Numeral 80 represents the trigger guard depending from the frame 12. Numeral 81 represents the trigger plate from which the trigger member 82 depends, this trigger plate being provided with an upstanding portion 83 and being 40 rockably mounted on the pin 84.

Through a bore in the rear portion of the guard 80 extends the spring-pressed plunger 85, bearing against the trigger 82 to afford the necessary spring action therefor. 45

Pivotedly connected as at 86 at its rear end to the upstanding portion 83 of the trigger plate 81 is the trigger bar 87 which is provided with a small U-shaped yoke 88 on the free end of one of its legs, denoted by numeral 89 while its 50 other leg 90 is curved upwardly as at 91 to terminate within the said yoke. This trigger bar 87 has suitable guide means and terminates at its free end within the path of the shoulder 21 on the sliding hook 20. 55

Projecting forwardly from the trigger plate 81 is the neck portion 92 provided with a pair of diverging fingers 93-94 between which the pin 95 on the rear end of the release bar 96 is disposed. The intermediate portion of this release bar 96 is enlarged as at 97 and provided with an elongated slot 98 therein in which engages the stud 99 projecting through the pawl 100 which has a hook-head 101 thereon. A lug 102 on the 60 enlarged intermediate portion 97 of the bar 96 is engageable with the projection 103 on the pawl 100, while the hook-head 101 on the pawl 100 is engageable with the lug 104 on the leg 70 of the hammer 69, as shown in Figure 2. 65

The release bar 96 is curved upwardly as at 105 at its forward end and provided with a notch 106 in its upper end. 70

As clearly shown in Fig. 2, an adjustment is provided for the trigger 82, whereby the same can 75

be set for single firing or automatic firing, or locked against firing at all.

The means generally referred to by numeral 114 is employed for converting the gun from an automatic to a semi-automatic, and a single shot rifle, and will not form part of the present disclosure.

The magazine locking mechanism includes a connecting rod 143 which is connected at its forward end pivotally to the cam detent 41. This rod 143 is disposed through the guide opening 145 on the bottom of the intermediate guide or magazine holder 117 and through the guideway 146 on the holder 31, backwardly of which the rod 143 is constructed for threaded disposition through the ears 148 on the intermediate portion of the U-shaped pusher 149, which is provided with rearwardly extending fingers 150 for engagement with the claw heads 25 of the arms 19-20.

A coiled spring 151 is adapted for interposition between the collar 152 on the rod 143 and a forward part of the holder 31. Manifestly, when the cam 41 is rotated, the rod 143 will be forced rearwardly against the tension of the spring 151 and when this cam 41 passes its center point, the spring 151 will hold the rod in projected position with the finger 150 forcing the claw heads 25 outwardly and rearwardly and partly holding the block 9 in retracted position. This obviously prevents firing of the rifle during the act of removing or replacing the magazine. The outward movement of the claw heads 25 prevent engagement of the same with the cartridge head and allows the magazine to be removed while containing cartridges.

The function of feeding the cartridges from the magazine to the firing chamber proceeds as follows. Assuming that a cartridge has been fired and the block is moving backwardly. The particular claw 28 engaging a cartridge head in the magazine pulls the cartridge by its head and in so moving the cartridge will actually pivot or wheel the same and cause it to ride under its adjacent spring finger 58, while the other spring finger is retaining the bullet end of the cartridge.

As the claw heads ride along the tracks 59, one without engaging the cartridge and the other engaged with the cartridge head, the cartridge will be wheeled around until it rides into the space between the free end portions of the fingers 58-58. When the cartridge reaches this position, both claw members 27 engage the cartridge head on opposite side portions thereof and as the block continues to move rearwardly, the same will lift up the lower end of the swingable incline or guide 66, and the head of the cartridge will engage into the notch 61 of the rotary guide 60 and between the flanges 62 thereof. In this movement, the cartridge clears the swingable guide 66 and when the block begins to move forwardly, the pusher 29 on the block will force the cartridge forwardly between the flanges 62 on the rockable guide 60 and up the incline 66 to stop in the firing chamber 7 of the barrel 5. When the block reaches this point and is actually in closed position, the mechanism is ready for the firing of the cartridge.

It can be seen that numeral 9' represents the movable detector arm having a fulcrum at 6', and this bar is provided with a boss a. This boss projects upwardly into a slot in the underside of the breech block 9 and is clearly shown. The empty shell is gripped by the two extractors b-c and as the breech block moves rearwardly the

head of the shell strikes the ejector board a and is knocked outwardly through the slot in the right side of the breech shell.

Referring to Figure 2, there can be seen the cartridges in the chamber and the lock mechanism in position to fire the same. The trigger bar 87 is connected to the trigger plate 81 by its pin 86 resting upon the boss 103 of the pawl 100, with the shoulder 90 against the boss 103 and is held firmly in this position through the spring tension of the two legs 89-91 of the bar 87, as the end of the leg 89 is held down at 88 through contact with the shoulder 21 on the bar 20, safety bar 107 is moved so that trigger enters notch 108.

When the trigger 82 is pulled rearward safety bar 107 moves so that trigger enters notch 108 and bar 87 moves forward, the shoulder 90 forcing the pawl 100 forward and disengaging the part 101 from the boss 104 on the hammer 69. Furthermore, when the yoke 88 has passed forwardly of the shoulder 21, the spring tension of spring 87 is released, thereupon the shoulder 90 slips past the boss 103 and the pawl 100 is returned to its original position by a suitable spring. The hammer 69 being released from the pawl 100 springs upward and strikes firing pin 15 driving it forward and firing the cartridge in the chamber. The pressure from the powder explosion forces the breech block 9 rearward against the tension of spring 10. The block 9 forces the hammer 69 back to its original position where it is again held by the pawl 100. The block 9 moves rearward until stopped by striking the rear of the breech shell and is then forced forward to its original position by the spring 10. When trigger 82 is released, the bar 87 moves rearward and the yoke 88 is forced down by 21 and shoulder 90 engages against the boss 103, thus completing the cycle. Each pull of trigger results in firing one shot.

While the foregoing specification sets forth the invention in specific terms, it is to be understood that numerous changes in the shape, size and materials may be resorted to without departing from the spirit and scope of the invention as claimed hereinafter.

Having thus described my invention, what I claim as new is:

1. In combination, a gun including a barrel, a breech and a bolt in the breech; an elongated magazine attached to the barrel and extending longitudinally thereof, said magazine being of a width to receive ammunition disposed transversely therein, means for forcing the ammunition in the magazine to the breech end thereof, means at the breech for removing the ammunition singly from the magazine and wheeling the same into firing position in the breech, said breech end of the magazine being provided with ammunition retaining spring fingers, said means for removing the ammunition including a claw operative between the fingers of the magazine to engage the ammunition, and a bifurcated spring member at the breech end of the magazine for alining the ammunition before it is finally forced into firing position.

2. In combination, a gun including a barrel, a breech and a bolt in the breech; an elongated magazine attached to the barrel and extending longitudinally thereof, said magazine being of a width to receive ammunition disposed transversely therein, means for forcing the ammunition in the magazine to the breech end thereof, means at the breech for removing the ammunition singly from the magazine and wheel-

ing the same into firing position in the breech, the breech end of the magazine being provided with an arcuate cut out portion along the edge portion on which a piece of ammunition can ride and wheel as it is extracted from the magazine.

5. In combination, a gun including a barrel, a breech and a bolt in the breech; an elongated magazine attached to the barrel and extending longitudinally thereof, said magazine being of a width to receive ammunition disposed transversely therein, means for forcing the ammunition in the magazine to the breech end thereof, means at the breech for removing the ammunition singly from the magazine and wheeling the same into firing position in the breech, the breech end of the magazine being provided with an arcuate cut out portion along the edge portion of which a piece of ammunition can ride and wheel as it is extracted from the magazine,

10 20 said end of the magazine being longitudinally slit and of spring material.

4. In combination, a gun including a barrel, a breech and a bolt in the breech; an elongated magazine attached to the barrel and extending longitudinally thereof, said magazine being of a width to receive ammunition disposed transversely therein, means for forcing the ammunition in the magazine to the breech end thereof, means at the breech for removing the ammunition singly from the magazine and wheeling the same into firing position in the breech, and a swingable guide at the breech adapted to assume an inclined position to catch a piece of ammunition when it has been wheeled into position by

15 25 30 35 the last mentioned means.

5. In combination, a gun including a barrel, a breech and a bolt in the breech; an elongated magazine attached to the barrel and extending longitudinally thereof, said magazine being of a width to receive ammunition disposed transversely therein, means for forcing the ammunition in the magazine to the breech end thereof, means at the breech for removing the ammunition singly from the magazine and wheeling the same into firing position in the breech, a swingable guide at the breech adapted to assume an inclined position to catch a piece of ammunition when it has been wheeled into position by the last mentioned means, said guide being provided with a spring for normally holding the same in an inclined position.

6. In combination, a gun including a barrel, a breech and a bolt in the breech; an elongated magazine attached to the barrel and extending longitudinally thereof, said magazine being of a width to receive ammunition disposed transversely therein, means for forcing the ammunition in the magazine to the breech end thereof, means at the breech for removing the ammunition singly from the magazine and wheeling the same into firing position in the breech, a swingable guide at the breech adapted to assume an inclined position to catch a piece of ammunition when it has been wheeled into position by the last mentioned means, and a rockable member in the breech responsive to the action of the bolt for elevating the ammunition to a position so that the nose thereof can rise on the guide when the bolt is moved to locked position.

ROY CLIFTON ROBERTSON. 35
